(57) **CLAIM**

The ornamental design for a multi-function printer, as shown and described.

DESCRIPTION

FIG. 1 is a first perspective view of a multi-function printer showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

Portions of the design in evenly-spaced broken lines represent unclaimed portions of the multi-function printer. The dash-dot-dash broken lines represent the boundary between the claimed and unclaimed portions and also form no part of the claim.
